UNITED STATES PATENT OFFICE.

CHARLES C. DUFOUR, OF BUTLER, PENNSYLVANIA.

CAR-ROOF.

1,116,037.

Specification of Letters Patent.

Patented Nov. 3, 1914.

Continuation of application Serial No. 762,350, filed April 19, 1913. This application filed February 26, 1914. Serial No. 821,137.

To all whom it may concern:

Be it known that I, CHARLES C. DUFOUR, residing at Butler, in the county of Butler and State of Pennsylvania, citizen of the 5 United States, have invented or discovered certain new and useful Improvements in Car-Roofs, of which improvement the following is a specification.

My invention relates to car roofs, and the 10 object thereof is to provide a construction which may be easily assembled and repaired, and which will have the required flexibility to resist, without forming leakage cracks, the torsion strains met in such roofs.

15 A further object of my invention is to provide a capping for adjacent free edges of the roof sheets, which capping, in conjunction with a particular shaping of such sheets, will effectively prevent, under service and test 20 conditions, the ingress of water to the car.

In the accompanying sheets of drawings, which form part of my specification, I have illustrated two embodiments of my invention:

Figure 1 is a transverse sectional view of 25 a portion of a car roof; Fig. 2 a sectional view taken on the line II—II, Fig. 1, showing also a portion only of the roof, but to enlarged scale; Fig. 3 an isometric view of a roof unit; and Fig. 4 a view similar to Fig. 30 2, but showing a modification of the construction illustrated therein.

In the several figures like numerals are used to designate like parts.

One feature of my invention concerns the 35 general construction of car roofs to the end that they may be built up in separate units, the several parts of which may be independently assembled and riveted or otherwise secured together, each unit being subsequently attached to the body of the car. To 40 such end the transverse and longitudinal frame members are, in this embodiment of my invention, connected together to form a plurality of adjacently-disposed transverse 45 units or roof segments.

Referring first to Figs. 1, 2 and 3, each unit comprises two carlines 1 and 1^a and purlins 2 extending between and riveted to the carlines, which extend continuously from 50 one side of the car to the other and are symmetrical about the longitudinal center line

of the car. Each carline is preferably made of a steel plate bent into Z-bar shape, thus affording rigidity without a sacrifice of head room. The purlins are formed of pressed 55 sheet metal, and are U-shaped having outstanding flanges whereby they are riveted to the intermediate leg of the carlines. The roof sheets 3 are fitted upon the units thus formed, which units may then be secured to 60 the side plates 4 of the car by means of bolts 5 and 5^a, the carlines being provided with an integral downwardly bent lug 6 for this purpose. As will readily be seen, a suitable space intervenes between adjacent carlines to 65 receive brackets for attaching the roof caps, the preferred construction of which will be presently explained. A complete roof unit thus formed is illustrated in Fig. 3. In the finished roof the adjacent carlines of adjacent units are preferably not connected to 70 each other, thus affording greater flexibility of the roof frame, so that there will be less liability of its being damaged by the warping and swaging of the car when traveling. 75 In case only a portion of the roof is injured in an accident, the injured unit may be separately repaired or replaced without dismantling the whole roof structure.

In Fig. 4 I have illustrated a combination 80 steel and wood roof, showing the adaptability of my improvements to roofs of this character. The carlines 1^b are of the same general shape and construction as those of the all-steel roof, but the purlins or nailing 85 strips 7 are made of wood attached by means of bolts 8 to a suitable pressed channel 9, which in turn is riveted to the carlines. Weather boards 10 are nailed to the strips 7, and form a support for the roof sheets 3^a, 90 which may be of lighter construction than the plates 3 of the all-steel roof. As in the case of the all-steel roof, the combination roof is made up of independent disconnected units, which may be separately removed at 95 any time.

The second feature of my invention concerns the weather roofing means at the joints formed between adjacent roof sheets. It is well known that the purchasers of cars 100 require the roofs to be subjected to a test known as the "hose test," wherein a stream

of water is played at high velocity upon the roof substantially in the plane thereof, it being considered that the conditions of actual service may be quite as severe as the 5 test. Heretofore, in some car roofs the adjacent sides of the roof plates have been turned upwardly and a metal cap, extending over and inclosing the up-turned ends of the sheets, has been clamped to the roof, the 10 edges of such cap bearing upon the roof sheets but not being connected thereto. Of this construction it has been found that water under relatively high velocity, when played upon the roof, finds its way beneath the 15 edges of the caps and over the up-turned ends of the sheets and into the car. To overcome this point of weakness I provide a double cap for such joints, and form a water-deflecting ridge in the roof sheets between 20 the downwardly-extending legs of the caps, so that such water as may be forced between the roof sheet and the outer cap will be deflected upwardly against the side of the inner cap, rather than over the up-turned end of 25 the roof sheet as in former constructions.

Referring again to the drawings, and particularly to Figs. 1 and 2, the roof sheets 3 have up-turned legs 11 adjacent to the carlines, and ledges 12 adapted to bear upon the 30 tops of the carlines as shown. Also, these sheets are provided with water-deflecting ridges 13 spaced a short distance from the carlines and extending parallel to them. An inner cap 14 extends over the legs 11 and 35 preferably bears upon the sheets 3 between each leg 11 and ridge 13, while the outer cap 15 includes the inner cap and bears upon the sheets 3 on the opposite or outer sides of the ridge. In order to clamp the sheets to the 40 roof I provide a bracket 20, which may be secured to the tops of the caps by means of rivets 16, and which may extend into the space between adjacent carlines. These brackets are provided with threaded holes to 45 receive bolts 17, which extend through the spacing member 18, there being a suitable bolt lock 19 provided to prevent the bolts from becoming loose. The inner cap 14 is in contact with the outer cap 15 only at the 50 brackets 20, thus leaving a space between the sheets for the passage of water from one side of the inner cap to the other. The ends of the caps are bent downwardly at the side of the car and extend over a strip of flashing 55 21 secured to rectangular fascia plate 22, which is attached to the siding 23 after such siding has been secured to the side plates 4.

The roof cap construction shown in Fig. 60 4 is, in all essential respects, the same as that shown in Fig. 2 and described above, the only difference being that the caps 14^a and 15^a are shallower.

Considering each built-up unit of the roof 65 as a carline, it will be observed that the roof

sheets lie within the carlines, and the caps span the space between them, rather than the sheets extending between, and the caps over the carlines.

I claim as my invention:

1. In a car construction, the combination with oppositely-disposed side plates, of a plurality of roof units each comprising roof sheets and supporting members therefor, said units being attached at their ends to 70 said side plates and extending transversely of the car, the adjacent units being unattached to each other in planes transversely of the said plates and separately removable from the car. 75

2. In a car construction, the combination with a car frame having as a part thereof oppositely-disposed side plates, of a roof comprising a plurality of separately removable units attached at their opposite ends to 80 said side plates, but unattached to each other in planes transversely of the said plates, each unit comprising two carlines with purlins extending between and rigidly secured to them. 85

3. In a car construction, the combination with a car frame having as a part thereof oppositely disposed side plates, of a roof comprising a plurality of separately removable units attached at their opposite ends to 90 said side plates, but otherwise unattached to each other in planes transversely of the said plates; each unit comprising two spaced carlines consisting of Z-bars, and U-shaped purlins having outstanding flanges attached 95 to the substantially horizontal legs of said Z-bars. 100

4. In a car roof construction the combination of a roof frame, metal sheets covering said frame and having their adjacent edges turned upwardly, inner and outer caps extending over said sheet edges, the free edges of said outer cap movably bearing upon said roof sheets, and upwardly extending water deflecting ridges on said sheets between said inner and outer caps. 105

5. In a car roof construction, the combination with a carline, and purlins extending from each side thereof, of roof sheets terminating with upturned ends at said carline and provided with upwardly-extending water-deflecting ridges, an inner cap extending over said upturned sheet ends and bearing upon said sheets between their upturned ends and said ridges, an outer cap inclosing said inner cap and bearing upon said sheets beyond said ridges, and means for attaching said caps to said carline. 115

6. In a car roof construction, the combination with a carline, and purlins extending from each side thereof, of roof sheets terminating with upturned ends at said carline and provided with upwardly-extending water-deflecting ridges, outer and inner caps extending over the upturned ends of said 120 125 130

sheets, the free edges of said outer caps bearing upon said sheets and inclosing said ridge, and the free edges of said inner cap being between said ridge and said upturned sheet 5 ends, and passageways between the tops of said caps affording communication from one side to the other of said inner cap.

In testimony whereof I have hereunto set my hand.

CHARLES C. DUFOUR.
